UNITED STATES PATENT OFFICE.

BERN S. SCHOENKERMAN, OF MILWAUKEE, WISCONSIN.

TABLET-PRESS.

1,344,091.

Specification of Letters Patent. Patented June 22, 1920.

Application filed August 9, 1919. Serial No. 316,466.

To all whom it may concern:

Be it known that I, BERN S. SCHOENKERMAN, a citizen of the United States, and resident of Milwaukee, in the county of Milwaukee and State of Wisconsin, have invented new and useful Improvements in Tablet-Presses, of which the following is a description, reference being had to the accompanying drawings, which are a part of this specification.

The present invention relates to certain new and useful improvements in a tablet press and method of making tablets.

One object of the present invention is to provide a tablet press so constructed that the ordinary layman or druggist's apprentice can manufacture tablets thereby and which will be of such compact structure that the same may be manufactured at an extremely low price and which will not be unwieldy to handle.

Another object of this invention is to provide a novel form of tablet press in which the dies may be readily removed therefrom for the substitution of dies of various sizes whereby the press may be adapted for use in making tablets of any desired shape or form.

A further object of this invention is to provide a tablet press of the class described having means for positioning the bed plate and die plate upon the machine so that the material receiving pockets will be in line with the pressing member and a substantial cup shaped bed plate for receiving the tablets after they have been formed.

A still further object of the present invention is to provide a tablet press of the class described and the herein-described method of making tablets from various materials.

With the above and other objects in view which will appear as the description proceeds, my invention resides in the novel construction, combination and arrangement of parts substantially as hereinafter described and more particularly defined by the appended claims, it being understood that such changes in the precise embodiment of the herein-described invention may be made as come within the scope of the claims.

In the accompanying drawing I have illustrated one complete example of the physical embodiment of my invention constructed according to the best mode I have so far devised for the practical application of the principles thereof, and in which:

Figure 1 is a side plan view of a tablet press embodying the various features of my invention, parts being broken away and in section to more clearly illustrate the details of construction.

Fig. 2 is a sectional view through the press, said view being taken on the line 2—2 of Fig. 3.

Fig. 3 is a sectional view taken on the line 3—3 of Fig. 1.

Fig. 4 is a perspective view of the cup shaped pocket member for receiving the tablets after they have been formed, and

Fig. 5 is a perspective view of the die plate having the material receiving pockets therein.

Referring now more particularly to the accompanying drawing, 6 designates a suitable press standard having a work receiving base 7 and a vertically bored arm 8 disposed above said base; 9 a plunger shaft mounted in the vertical bore of the arm 8 and normally urged up to a position spaced from the base 7 by means of an extensible spring 10 disposed in a pocket formed in the arm 8 and bearing against a lever 11 formed on the upper end of the plunger 9; and 12 an operating lever pivoted as at 13 in the upper bifurcated end of the arm 8 and provided with a cam surface 14 adjacent its pivot 13 and bearing upon the top of plunger 9 whereby the plunger 9 is depressed against the action of its spring 10 when the handle 12 is moved to the left with reference to the drawing.

As best shown in Fig. 2, the lower end of the plunger 9 which projects below the arm 8 is recessed or counterbored as at 15, for receiving a stud shaft or lug formed on the top side of a disk 17, the stud shaft 16 being readily removably secured in the recess 15 by means of a dowel or cotter pin 18 passed through alined openings in the plunger 9 and stud shaft 16. Formed on the end side of the disk 17 is a plurality of "punches" or compressing members 19 which are adapted to work within material receiving pockets 20 formed in a readily removable die plate 21. As best shown in Figs. 1, 3 and 4, the mouth of the material receiving pockets 20 is slightly flared or curved outwardly as at 22 to assist in guiding the compressing members 19 therein.

In general operation, the removable die plate is positioned on a solid readily removable bed plate 23, by means to be later de-

scribed, so that the members 19 will be in line with the pockets 20 and after the material to be formed into tablets has been 5 depressed, or moved to the left with reference to the drawing, to bring or move the members 19 into the pockets 20 and firmly compress the material, not shown, within the pockets into a tablet form, after which 10 the lever 11 is allowed to move to upright position under action of its spring 10. The solid bed plate 23 is then replaced by a substantially cup shaped bed plate having a closed bottom 24 and an annular side or 15 flange 25, and when the same is in position the handle 12 is again depressed, the members 19 forcing the tablets formed by the operation just described, into the recess formed by the sides 25 of said cup shaped 20 container. Thus the tablets may be readily removed and placed in a suitable container, and to make a new set of tablets, the operation just described is repeated.

In order to insure the positioning of the 25 die plate 21 so that the pockets 20 will register with the members 19, the base 7 of the standard 6 has formed at its inner end a recessed portion 26 having its inner face curved to conform with the periphery of the 30 die plate and said bed plate and is also provided with a central inwardly extending projection or lug 27 adapted to be engaged in a correspondingly shaped recess 28 formed in the sides of said die plate and bed plates. 35 The notch 28 of the die plate 21 is so positioned that when the same is engaged with the lug 27 the pockets 20 will be in register with the members 19.

From the foregoing description taken in 40 connection with the accompanying drawing, it will be readily apparent that I provide a simple tablet press in which the disk 17 and the die plate 21 may be readily detached and others secured thereto whereby the 45 press may be readily adapted for use in forming tablets of various sizes and shapes, and that by the method of forming the tablets as described in the operation of the press, it is possible for the ordinary druggist's apprentice to make tablets without 50 any previous experience.

For convenience in placing the die plate 21 and the plate 23 in the press without wasting any of the material in the pockets 55 20, I provide a plurality of spaced apart

lugs 29 on the plate 23 engageable in openings 30 in the plate 21.

What I claim as my invention is:

1. A tablet press of the class described comprising a base, a removable bed plate, a die plate having an aperture therein, a plunger adapted to be passed into said aperture to compress materials disposed therein whereby to form the same into a tablet, and a cup shaped bed plate adapted to be substituted for said first mentioned bed plate after the tablets have been formed whereby to receive the tablets and permit their ready removal from the aperture in the die plate.

2. A tablet press of the class described comprising a fixed base, a removable bed plate, a die plate removably positioned on the bed plate, a plurality of material receiving pockets extending through said die plate and having their bottoms closed by said bed plate, a movable disk, a plurality of compressing members carried by said disk and adapted to engage in said pockets, means for moving said disk to move said compressing members into said pockets to 80 form materials disposed therein into tablet form, and a cup shaped removable bed plate adapted to be substituted for said first mentioned bed plate, said compressing members being operated to push the tablets formed 85 in said pockets into said cup shaped bed plate for ready removal.

3. A device of the class described comprising a fixed base, a removable bed plate, a die plate removably positioned on the bed plate, a plurality of material receiving pockets extending through the die plate and having their bottoms closed by said bed plate, a movable disk, a plurality of compressing members carried by said disk and engageable in said pockets, means for moving said disk to bring the compressing members into said pockets to form materials disposed therein into tablet form, a removable cup shaped bed plate adapted to be substituted 95 for said first mentioned bed plate, said compressing members being operable to push the tablets formed in said pocket into said cup shaped bed plate for ready removal, and coöoperating means between said fixed 100 base and said removable bed plates and die plate whereby said plates are readily and properly positioned upon the fixed base.

In testimony whereof I affix my signature.

BERN S. SCHOENKERMAN.
